UNITED STATES PATENT OFFICE.

ALBERT BALL, OF CLAREMONT, NEW HAMPSHIRE, ASSIGNOR TO THE SULLIVAN MACHINE COMPANY, OF SAME PLACE.

SAND-BAND.

SPECIFICATION forming part of Letters Patent No. 447,287, dated March 3, 1891.

Application filed July 21, 1890. Serial No. 359,351. (No model.)

To all whom it may concern:

Be it known that I, ALBERT BALL, a resident of Claremont, in the county of Sullivan and State of New Hampshire, have invented 5 certain new and useful Improvements in Sand-Bands; and I do hereby declare the following to be a full, clear, and exact description of the invention, such as will enable others skilled in the art to which it pertains to make 10 and use the same.

The object of the invention is to simplify and cheapen the construction of sand-bands and of the means of connecting them with an axle of a wheeled vehicle.

15 Heretofore the shells of sand-bands have been provided with an inner inturned flange which was clamped between a screw-threaded nut placed within the shell adjacent to the flange and an exteriorly screw-threaded 20 holder fitted on the axle. This holder has been made in the form of a mutilated or incomplete ring, being slotted for the reception of the axle. An extension or arm of said holder was embraced by the ordinary yoke, 25 which holds together the wooden and metallic sections of the usual form of carriage-axle, and was thereby clamped to the bottom of the axle. By the present improvement the inner screw-threaded ring is dispensed with, and the 30 inner end of the shell is provided with a head secured directly thereto by swaging and having a screw-threaded opening adapted to screw upon the axle. The aforesaid holder is provided exteriorly on its main part with 35 screw-threads, which are continuous with others formed on the axle, upon which the exteriorly screw-threaded head of the sand-band is screwed.

The invention consists in the construction 40 herein described, and particularly pointed out.

In the drawings, Figure 1 is a partial longitudinal section of sand band or box. Fig. 2 is a central longitudinal section of a modified 45 form. Fig. 3 is a similar section showing the band applied to the axle. Figs. 4, 6, 7, 9, and 10 are like sections of modifications. Fig. 5 is a section of the head shown in place in Fig. 6, and Fig. 8 is a plan showing the interior of 50 sand-box.

Referring to Fig. 1, the letter A indicates a

sheet-metal shell, and D a head made of malleable metal. This head is provided with a screw-threaded opening adapted to be screwed directly upon the axle, as indicated in Fig. 3. 55 It has also at P a groove adapted to receive the edge of the shell A. After said shell has been entered in the groove the metal of the head is forced or swaged upon the shell, so as to hold it tightly, by which means the parts 60 are securely fastened together. By preference the edge of the sheet-metal shell that enters the groove is folded or rolled upon itself or otherwise slightly enlarged, and the metal of the head is then forced over and 65 upon this edge, making a strong joint. Figs. 2 and 3 show a joint without such enlargement of the shell.

F is an axle-holder, and H H' are sand-outlets.

I am aware that the shell of a sand band or box has been clamped between an interior ring and the holder, and also that such interior ring has been dispensed with and the shell provided with a head soldered thereto, 75 and such devices are not of my invention, it being characteristic of my improvement that the head is made of metal that is malleable or whose rim can be made so, and that it is provided with a groove, ledge, or seat adapted 80 to receive the edge of the shell by swaging or like means.

As shown in Fig. 4, the shell is provided with an inturned flange C, and the rim of the head D is made smaller than the form first 85 described.

R is a flange or shoulder, between which and the edge S of the head the flange C is received by forcing the edge S, previously beveled, as shown in Fig. 5, upon the flange.

90 A similar construction is illustrated in Figs. 6, 7, and 8, the shoulder being located in the exterior of the flange of the shell and the turned-down edge d on the interior. This edge is preferably cut or slotted at intervals 95 in this and also in other forms of the improvement to facilitate turning down, swaging, or clinching the same upon the shell or its flange.

In Fig. 9 is shown a form in which a wide groove or channel is formed around the ring 100 portion D of the head, into which groove is fitted a collar formed on the annular band D'.

The annular ridges that form said groove, or one of them, is swaged or forced down upon the edges or edge of the collar in such manner as to securely hold or grip it. The outer 5 edge of the band D' is united to the lower edge of the shell by a lap-joint. The edge if made continuous can be expanded and turned outward and down, but not so conveniently as when divided in sections, as indicated.

10 In Fig. 9 is shown a modification in which the edge of the shell is expanded and made to embrace the rim of the head and then forced upon said rim to lock them together. The head is preferably made larger than the 15 shell just below the expanded part, so that the expansion of the shell partially surrounds the edge of the rim of the head.

T indicates an inturned edge of the sheet-metal shell, the purpose of which is to stiffen 20 the joint.

By the above-described selection of material and suitable construction of parts I am able to make a joint between the shell and head of a sand-box more stable and more 25 economical than by soldering, the edge of the shell being simply gripped or pinched between opposing parts of the head, one of which is forced upon it by use of well-known means, or in some cases the shell can be made 30 to embrace the edge of the head, as explained.

I am aware that caps of less diameter than the hub have been fitted upon a rim or head secured upon the axle by means of lugs and notches in the adjoining parts or by means 35 of a close fitting of the parts. By my improvement the head is made malleable, and a part of it is swaged or forced upon the band.

This band is larger in diameter than the end of the hub and embraces the same, and is therefore liable to greater strain, owing to its 40 exposed position and larger size, and the locks or the friction devices before employed are insufficient to securely hold the parts in place.

Having thus described my invention, what I desire to secure by Letters Patent is— 45

1. In a sand band or box, a shell provided with a head of malleable metal having a groove or its equivalent for the reception of the edge of the shell, said edge being gripped by an edge of the metal of the head forced 50 down upon the same, substantially as set forth.

2. In a sand band or box, a shell provided with a head of malleable metal having a groove or its equivalent for the reception of 55 the edge of the shell, said edge being gripped by an edge of the metal of the head forced down upon the same, said edge being slotted or cut in sections, substantially as set forth.

3. In a sand band or box, a shell having a 60 folded or enlarged edge and provided with a head of malleable metal having a groove or its equivalent for the reception of the edge of the shell, said edge being gripped by an edge of the metal of the head forced down 65 upon the same, substantially as set forth.

In testimony whereof I have signed this specification in the presence of two subscribing witnesses.

ALBERT BALL.
